UNITED STATES PATENT OFFICE.

JOHN E. HANRAHAN, OF BALTIMORE, MARYLAND, ASSIGNOR TO THE AD-ATYPE MATRIX COMPANY, OF BALTIMORE, MARYLAND, A CORPORATION OF DELAWARE.

PROCESS OF MAKING MATRICES.

1,092,709.

Specification of Letters Patent.

Patented Apr. 7, 1914.

Application filed August 8, 1913. Serial No. 783,735.

To all whom it may concern:

Be it known that I, JOHN E. HANRAHAN, a citizen of the United States, residing at Baltimore, State of Maryland, have invented certain new and useful Improvements in Processes of Making Matrices; and I do hereby declare the following to be a full, clear, and exact description of the invention, such as will enable others skilled in the art to which it appertains to make and use the same.

This invention relates to a process for producing matrices and has for its object to provide a method which will be more efficient, expeditious, and less expensive than those now in use.

To these ends the invention consists in the novel steps and combinations of steps constituting my method as will be more fully hereinafter disclosed and particularly pointed out in the claims.

Referring to the accompanying drawings forming a part of this specification in which like numerals designate like parts in all the views:—Figure 1 is a diagrammatic view of a holder or clamp for obtaining an impression in wood or other soft material of the letter or other object of which it is desired to make a matrix; Fig. 2, is a perspective view of a standard type letter such as is employed in Fig. 1; Fig. 3, is a view partly in section of a clamp, the wood and type face illustrated in Figs. 1 and 2, as well as of a type face holder to which the said type face is to be secured; Fig. 4, illustrates the type face holder after the type face has been secured thereto; Fig. 5, shows the type face holder associated with a matrix blank, held in a frame, and temporarily secured together; Fig. 6, illustrates the type face holder and matrix blank to which is secured the type face before being covered with wax; Fig. 7, is an edge view of the parts shown in Fig. 6; Fig. 8, is a plurality of type face holders, type faces and matrix-blank holders assembled ready for being covered with wax before receiving a coating of copper; Fig. 9, is a sectional view taken on the line 9—9 of Fig. 8, after the parts have received their coating of wax; Fig. 10, is a sectional edge view of the completed matrix after being separated from the type face holder and Fig. 11 is a plan view of the parts shown in Fig. 10.

55 In carrying out my invention I provide

any suitable clamping means such as 1, and secure thereto as by the screw 2, a block of wood or other soft material 3. The block 3 is accurately shaped to the exact face dimensions of the type face holder 4 to be described below, so that when the two are brought together face to face, as in Fig. 3, the outer edges will be even all around. I also suitably secure in the clamp 1, as by means of the screw 5, guide piece 6, and 60 screw 9, a type body 7 having a type face or other design of standard dimensions. The type face 8 is made to contact with the soft block 3 as indicated, and the parts are so positioned that an impression made in the 65 soft block by the face 8 will be located on said block in the precise position, relative to its edges, it is desired the said type face to occupy on the type face holder 4 relative to its edges, as will be clear from Fig. 4. Further, as will also be clear from Fig. 4, if the axes of the type face or other design is not located exactly at right angles to the edges of the holder 4, then the letter as well as the matrix will appear turned or slanted and 70 make a bad appearance in print. Consequently, in order to not only locate the face 8 correctly with respect to the edges of the block 3, but also to insure the axes of said face 8 being perpendicular to said edges, 75 I so design the members of the clamp 1 that when the type body 7 is held as indicated in Fig. 1, the impression to be made in the block 3 will be correctly located in all respects. The type body being slidingly held 80 as indicated, a slight blow is imparted to its end and the face 8 driven into the block 3 to form the cavity 12. The body 7 is now removed secured in a vise or other clamping means, when the face 8 is cut from the 85 body 7, as by sawing along the dotted line 10, Fig. 2. The face 8 being thus severed from the body 7, its base is thinned down as by filing until it is a mere film, when it is 90 reinserted into the cavity 12 in the block 3, 95 and the face of the holder 4, having been coated with a thin film of an easily melted solder such as the well known alloy of zinc and tin, the members 3 and 4 are brought together as indicated in Fig. 3, with the base 100 11 of the type face next the solder coated surface of the holder 4. The impression 12 having been accurately located and orientated relative to the edges of the block 3, and the 105 said block being accurately of the same size 110

as the holder 4, it is evident that the type face will now occupy a position on the holder 4 in all respects the same as it occupies on the block 3. The parts are now clamped together by any suitable means, such as the device 13, and heat applied as by the flame 14, whereupon the type-face or other design 8 will be sweated or soldered on to the said holder 4 and occupy some such position as 10 that indicated in Fig. 4.

It is important to observe that the procedure just described enables me to locate and to orientate the type-face 8 with the highest degree of accuracy relative to the 15 edges of the holder 4.

I next provide a matrix blank 15 preferably having two holes 16 and 17 and having precisely the same width as the holder 4 so it will accurately match the same as indicated in Fig. 6. This matrix blank, together with the holder 4 carrying the face 8, is next placed in the matrix blank holder 18, which they accurately fit, as indicated in Fig. 5, and the parts clamped together as by the 20 screw 20. It will now be again observed that since the type-face 8 was positioned with the utmost accuracy with relation to the edges of the holder 4, and since these 25 said edges accurately fit the edges of the matrix blank 15, and since the matrix blank holder 18 accurately fits both the members 4 and 15, that when the parts are clamped as indicated in Fig. 5, the type-face 8 must of necessity be positioned and orientated with 30 the greatest accuracy relative to the edges of the matrix blank 15. When in this position the members 4 and 15 are temporarily firmly secured together, as by means of a drop 21 of soft or other solder. By following 35 the foregoing procedure another character such as 22 may be secured on another holder 4, and the two characters and holders 4 may be secured to the same matrix blank 15 as indicated in Fig. 7.

40 After having thus secured one or more holders and type-faces to the blanks 15, I place them all together as indicated in Fig. 8 and coat them over with wax 25, being careful to work the wax well down over the 45 beveled edges 26 of the holes 16 and 17 so as more effectually to concentrate the deposit of copper on the type faces 8. I regard this as important, for, of course, the copper will deposit most abundantly on those conducting parts closest to the anode, and these faces 26 being nearer the anode than the type faces 8 and 22, would, unless covered with wax, receive copper to the exclusion of said type-faces. The series of blanks 15 50 being thus properly coated with wax, with the type-faces 8 and 22 exposed, the whole is suitably joined in an electrolytic bath and a coating 27 of copper deposited on and around said type-faces, thus forming accurate matrices of copper from said type-faces.

The matrices are next removed from the bath, stripped of their wax coatings, separated from their holders 4 and type-faces, and the cavities on their back faces, formerly occupied by the wax coatings, are filled with 70 type metal 28. This type metal is next smoothed off to make it even with the back surfaces of the matrices, and completed matrices result, having their characters or designs absolutely accurately reproduced from 75 the original patterns, and absolutely accurately positioned and orientated with respect to the edges of said matrices, all as indicated in Fig. 11. These said matrices are now ready for use in any suitable casting machine and absolutely accurate type may be cast therefrom in all respects the equal of those cast from the most costly matrices now employed.

It is obvious that those skilled in the art 80 may vary the details of the procedure as well as the order of the steps without departing from the spirit of my invention and therefore I do not wish to be limited to the above disclosure except as may be required by the 90 claims.

What I claim is:—

1. In a process for producing matrices the combination of steps which consists in providing a type face holder of the same width 95 as the finished matrix; providing a member of soft material of the same face dimensions as said holder; making an impression of the character it is desired to reproduce in said soft material; and securing said character 100 to said holder while held in said impression, substantially as described.

2. The process of producing matrices from standard type which consists in taking an impression of said type in a predetermined 105 position in material having predetermined face dimensions; transferring the face portion of said type from said impression to a holder having the same face dimensions and securing it in the same relative position on 110 said holder; and suitably preparing a matrix from the said face portion, substantially as described.

3. The process of producing matrices from standard type which consists in making an 115 impression from the face portion of said type in a block having the same width as the finished matrix; transferring said type face from said impression to a holder having the same width as said block and matrix; locating said type face on and securing it to 120 said holder in the same relative position it occupied in said block; and suitably forming a matrix from the said face portion, substantially as described.

4. The process of producing matrices from standard type which consists in making an impression from the face portion of said type in a block having the same width as the finished matrix; severing said face portion 130

from said type and replacing it in said impression; transferring said type face from said impression to a holder having the same width as said block and matrix; locating 5 said type face on and securing it to said holder in the same relative position it occupied in said block; and suitably forming a matrix from the said face portion, substantially as described.

10 5. The process of producing matrices from standard type which consists in making an impression from the face portion of said type in a predetermined position on a block of soft material having the same width as 15 the body of the finished matrix; severing said face portion from the body of said type and replacing it in said impression; transferring and securing said face portion to a similar predetermined position on a 20 holder having the same width as said block and matrix; suitably associating said holder and face portion with a perforated matrix blank; and forming a matrix from the parts thus assembled, substantially as described.

25 6. The process of producing matrices from standard type which consists in making an impression from the face portion of said type in a predetermined position on a block of soft material having the same width as 30 the body of the finished matrix; severing said face portion from the body of said type and replacing it in said impression; transferring and securing said face portion to a similar predetermined position on a 35 holder having the same width as said block and matrix; suitably associating said holder and face portion with a perforated matrix blank; coating said matrix blank with non-conducting material leaving said face portion exposed and forming a matrix from the parts thus assembled, substantially as described.

40 7. The process of producing matrices from standard type which consists in making an impression from the face portion of said type in a predetermined position on a block of soft material having the same width as the body of the finished matrix; severing said face portion from the body of said type 45 and replacing it in said impression; transferring and securing said face portion to a similar predetermined position on a holder having the same width as said block and

matrix; suitably associating said holder and face portion with a perforated matrix blank; 55 coating said matrix blank and a portion of the edges of its perforation with wax leaving said face portion exposed; depositing metal on said face portion; removing the wax; and filling in the cavities left by said 60 wax, substantially as described.

8. The process of producing matrices from standard type which consists in providing a matrix blank, a type face holder, and a block of soft material all having the same 65 width; making an impression of said type in said block in a predetermined position relative to the edges of said block; severing the type face from said type body and reinserting it into said impression; transferring said face portion to said holder and securing it to said holder in the same relative position it occupied on said block; temporarily securing said type face holder and type face to said matrix blank and causing 70 said type face to occupy the same position relative to the edges of said blank it occupied on said block; and suitably forming a 75 matrix from said type face, substantially as described.

80 9. The process of producing matrices from standard type which consists in taking an impression of said type; severing the face portion from the body of said type, smoothing it off and reinserting it in said impression; transferring said face portion to a holder and securing it in a predetermined position on said holder; temporarily soldering said holder and type face to a matrix blank having a perforation with said type 85 face occupying a predetermined position in said perforation; covering said blank and the edges of said perforation with wax; suitably depositing copper on said type face; separating said holder from the matrix thus 90 formed; removing said wax; filling in the cavity around said perforation occupied by said wax with metal; and smoothing off the said metal even with the body of said matrix, substantially as described.

95 100 In testimony whereof I affix my signature, in presence of two witnesses.
